UNITED STATES PATENT OFFICE.

WILLIAM A. LOUDON, OF CHICAGO, ILLINOIS.

WHEEL-TIRE.

No. 812,759.

Specification of Letters Patent.

Patented Feb. 13, 1906.

Application filed May 1, 1903. Renewed January 16, 1905. Serial No. 241,352.

To all whom it may concern:

Be it known that I, WILLIAM A. LOUDON, a citizen of the United States, residing at Chicago, in the county of Cook and State of Illinois, have invented a new and useful Wheel-Tire, of which the following is a specification.

My invention relates to improvements in wheel-tires in which a plurality of blocks of fibrous material, preferably wood, are arranged circumferentially around the wheel-felly or iron tire, and relates particularly to the manner of fastening the blocks to the wheel and to the arrangement of the blocks on the wheel; and the objects of my invention are, first, to provide a good traction-surface; second, to furnish a cheap, simple, and durable tire; third, to facilitate the easy and quick repair of the tire, and, fourth, to provide a plurality of rows of blocks side by side circumferentially arranged around the wheel. I attain these objects by the construction illustrated in the accompanying drawings, in which—

Figure 1 is a side elevation of a wheel embodying my invention. Fig. 1^a is an edge view of the same. Fig. 2 is a side elevation of a fragment of the wheel shown in Fig. 1 on an enlarged scale. Fig. 3 is a section of Fig. 2. Fig. 4 is an elevation of the inner faces of the segmental plates as they appear when attached to a wheel. Fig. 5 is an elevation of one form of clamping-ring used to secure the tire on the wheel. Fig. 5^a is a side elevation of another form of clamping-ring used to secure the tire on the wheel. Fig. 6 is a perspective view of one of the wooden blocks detached. Figs. 7, 8, and 9 are cross-sections similar to Fig. 3 of modified forms of construction. Fig. 10 is a fragmental longitudinal section through a wheel-rim, showing a modification; and Fig. 11 is a perspective view of still another modification.

Similar numerals refer to identical parts throughout the several views.

The wheel 15 consists of the ordinary hub 16, spokes 17, and felly 18, around which is fitted the iron band or tire 19. Resting against this iron band are the blocks 20, which I at present consider best to be made of wood, but may be of any material. The blocks 20 are substantially square in cross-section, one end of each block resting against the iron band 19 and the other end of each block extending out radially, subjected to the traction wear. To attain the necessary width of traction-surface, I provide a plurality of cir-

cumferential rows of blocks, which is one of the features of my invention. Another feature of my invention is to have the ends of the blocks resting against a flat iron band, 60 thus presenting a firm even surface for the blocks to abut against and making the blocks all interchangeable, so that a block taken from a supply on hand can be inserted wherever a block has been worn away or displaced. 65 The blocks 20 can be secured in their position by any suitable means. I have shown what I at present consider best adapted for the purpose. I prefer to have the iron band 19 integral with a side clamping-ring 21, as seen in 70 Figs. 3 and 5, forming substantially a T-shaped iron band. A portion of the ring 21 rests against the side of the felly 18 and a portion clamps the blocks 20 in a manner to be described. The outer edge of the ring 21 is 75 peened over inwardly, as at 22, to insure better contact with the adjoining blocks. On the opposite side of the felly 1 I provide segmental clamping-plates 23, which when placed in position side by side form a ring 80 similar to the ring 21, and they have their outer edges peened inwardly, as at 24, to insure better contact with the adjoining blocks. A groove or recess 25 is preferably provided 85 on the inner face of the plates 23, into which fits the band 19. To securely clamp the ring 21 and the plates 23 against the blocks 20, a bolt 26 is provided, preferably passing adjacent to the iron band 19, the base of the blocks being partly cut away to permit of such passage of said bolt, with its head on the outside of the ring 21 and its nut on the outside of the plate 23. A sufficient number of bolts 26 are used to securely hold the parts together. 90

The two outer rows of blocks 20, which are 95 adjacent to the ring 21 and the plates 23, are engaged by the inner faces of such ring and plates and by their respective peened-over edges 22 and 24 and are thus absolutely prevented from displacement. To prevent the 100 displacement of the intervening rows of blocks 20 and to hold the same in position, I provide the clenching-rings 27 between the rows of blocks. Each ring 27 is provided on its periphery with a bead or lateral projecting 105 rim 28, which impinges the adjacent wooden blocks when the nuts are turned on the bolts 26 to force the rows of the blocks together. The rings 27 serve as washers between the 110 rows of blocks and fit loosely over the band 19 and are cut away sufficiently to permit the free passage of the bolts 26.

To assemble the parts, the band or tire 19, with its integral ring 21, is secured around the felly 18 of the wheel in the ordinary manner. Then the wheel being preferably laid flat with the ring 21 downward, the bolts 26 are inserted through the holes provided for the same in the ring 21. Next the first row of blocks 20 is laid around the band 19 on the ring 21. Then the first clamping-ring 27 is slid over the band 19 and laid on the first row of blocks. Next another row of blocks 20 is laid around the band 19 on the clamping-ring 27, and so on, alternating a row of blocks 20 and a clamping-ring 27 until the whole width of the tire is complete. Of course the width of the tire is predetermined, so that a certain number of rows of blocks and rings will just fill the space between the ring 21 and the plates 23. The blocks 20 may or may not have the grooves 29 cut therein to receive the portions 22, 24, and 28. Finally, the segmental plates 23 are laid into position, and the nuts are screwed tightly upon the bolts 26, thus clamping all the blocks between the ring 21 and the plates 23.

In Fig. 7 is shown the ordinary construction of the wheel having the felly 18 surrounded by the iron tire or band 19 and my invention applied thereto by providing a separate ring 21, having the peened-over edge 22, on the one side of the felly and the segmental plates 23, having the peened-over edge 24, on the other side of the felly. In this construction I prefer to use the additional bolts 30, passing through the felly, besides the bolts 26 to clamp the blocks 20 between the ring 21 and the plates 23. I have also shown in Fig. 7 that instead of using the flat washer-like rings 27 I may employ the rings 31, which do not contact with the band 19, but simply rest against the beveled portion of the adjoining sides of the rows of blocks, and thus prevent any radial displacement of the blocks 20.

In Fig. 8 is shown a wheel having its felly 18 surrounded by a tire or band 19, having integral therewith the two clamping-flanges 32, which substantially correspond to the ring 21 and plates 23 in so far as that portion between which the blocks 20 are clamped is concerned. The clamping-flanges 32 are provided with the peened-over edges 33, similar to the edges 22 and 24, previously referred to. In the construction shown in Fig. 8 the blocks 20 are clamped in position and prevented from any radial displacement by small rods or cables 34 being forced in against the beveled adjacent sides of the rows of blocks, any convenient means (not shown) being provided to shorten the rows or cables 34.

Figs. 9 and 10 illustrate one mode of attaching my tire to a metallic wheel. The rim 19 of the wheel being metallic has integral

therewith the clamping-flanges 32. The blocks are arranged in rows and are clamped into position by the bolts 35, which have their screw-threaded ends projecting through the iron band or rim 19 and their other ends terminating in wedge-shaped bars 36, which are arranged to slightly overlap at the ends, as shown in Fig. 10, and contact with the beveled portion of the adjacent sides of the rows of blocks and tend to separate the rows of blocks when the nuts are turned on the screw-threaded ends of the bolts 35, thus wedging the blocks tightly between the flanges 32, against which the two outer rows of blocks rest.

It is obvious that the wooden blocks 20 could, if preferred, be secured to the metallic wheel by having only one of the flanges 32 integral with the rim 19 and segmental plates to take the place of the other flange with a number of bolts connecting the flange with the segmental plates, substantially as shown in Fig. 3, or the wooden blocks 20 may be secured to the metallic wheel by having a separate clamping-ring on one side of the rim 19 and the segmental plates on the other side connected by bolts, as shown in Fig. 7. It is also to be understood that I may use any means for holding the blocks in position and from being displaced radially; but I prefer using some one of the constructions shown. So long as a plurality of rows of blocks are secured to the periphery of a wheel, no matter what means are used for securing the same in place, the construction is within the meaning and scope of my invention, providing, however, that such blocks are capable of being removed separately and of being replaced by new blocks.

In Fig. 11 is shown still another modified form of constructing blocks on the periphery of a wheel, each block 20 being tapered slightly and inserted in a collar 37, which is secured to the rim 19 of the wheel by bolts or screws passing through the ears 38.

By my improved wheel-tire the wearing-surface is wood or other material, if preferable, and is capable of being removed and replaced in small sections. The great advantage of this construction is to provide a cushion-tread and means whereby when a certain portion of the tire becomes damaged only that portion of the tire which is damaged need be replaced, thus making use of every portion of the tire until it is worn out.

I am aware that previous to my invention wooden tires have been used and do not claim the idea of using wood for tires broadly; but

What I do claim, and desire to secure by Letters Patent, is—

1. In a wheel-tire the combination of a metallic band; a plurality of circumferential rows of wooden blocks and means for secur-

- ing said blocks in position, said means comprising side flanges and clamps capable of radial adjustment between said rows of blocks. 45
2. In a wheel-tire the combination of a plurality of circumferential rows of wooden blocks; a clamping-ring on one side of said rows, segmental clamping-plates on the opposite side of said rows, circumferential clamping-rings between said rows, and screw-bolts 50 connecting said clamping-rings and clamping plates. 55
3. In a wheel-tire the combination of a plurality of circumferential rows of wooden blocks; a clamping-ring integral with a metallic band; segmental clamping-plates provided with a recess to receive the edge of said band; clamping-rings provided with lateral-extending circumferential flanges, between the said rows; and clamping-bolts substantially 60 as specified. 65
4. In a wheel-tire the combination of a band, a plurality of circumferential rows of blocks and means for securing said blocks in position, said means comprising side flanges and clamps capable of lateral adjustment between said blocks. 70
5. In a wheel-tire the combination of a plurality of circumferential rows of blocks, a clamping-ring on one side of said rows, a 75 clamping-ring on the other side of said rows, clamping means between said rows, and screw-bolts connecting said two clamping-rings. 80
6. In a wheel-tire the combination of a plurality of circumferential rows of blocks, a clamping-ring integral with a band on one side of said blocks, a clamping-ring on the other side of said blocks, clamping-plates between said rows of blocks and clamping-bolts connecting said two clamping-rings. 85
7. A wheel-tire comprising a plurality of circumferential rows of blocks resting on a circumferential band and circumferential plates capable of lateral adjustment on said 90
- band between said rows of blocks and means for securing said blocks, band and plates together. 45
8. A wheel-tire comprising a plurality of circumferential rows of blocks resting against a band, a plurality of fastening-pieces capable of lateral adjustment to said band located between said rows of blocks for securing said blocks in position and means for clamping said blocks to said band. 50
9. In a wheel-tire a plurality of circumferential rows of blocks resting on a band and annular bands capable of lateral adjustment on said band between said rows of blocks and means for clamping said rows of blocks together laterally. 55
10. In a wheel-tire, a plurality of circumferential rows of blocks resting against a band, a plurality of fastening-pieces capable of lateral adjustment to said band located between said rows of blocks, and means for clamping said rows of blocks together laterally. 60
11. In a wheel-tire the combination of a band, a plurality of circumferential rows of blocks and means for securing said blocks in position on said band, said means comprising side flanges, metallic pieces secured against radial displacement between said blocks and clamping-bolts. 65
12. In a wheel-tire the combination of a plurality of circumferential rows of blocks, clamping-rings on either side of said rows, washers provided with lateral extensions between said rows and screw-bolts connecting said two clamping-rings. 70
- In testimony whereof I have signed my name to this specification in the presence of two subscribing witnesses. 75
